UNITED STATES PATENT OFFICE.

CARL H. MAYER, OF CHICAGO, ILLINOIS.

INDICATOR FOR PLAYER-PIANOS AND SIMILAR INSTRUMENTS.

1,373,752.

Specification of Letters Patent. Patented Apr. 5, 1921.

Application filed February 20, 1919. Serial No. 278,150.

To all whom it may concern:

Be it known that I, CARL H. MAYER, a citizen of the United States, residing at Chicago, in the county of Cook and State 5 of Illinois, have invented a certain new and useful Improvement in Indicators for Player-Pianos and Similar Instruments, of which the following is a full, clear, concise, and exact description, reference being had 10 to the accompanying drawings, forming a part of this specification.

My invention relates to improvements in player pianos and such like musical instruments, and has for its object to provide 15 means to facilitate the identifying of the note being sounded, with the like note key on the usual manual keyboard of the instrument.

Such instruments are usually provided 20 with what is called a tracker board which has a series of holes one corresponding with each note to be sounded and which holes are controlled in the playing of music by a paper strip provided with perforations 25 adapted to successively register with the several holes in the tracker bar as the strip is moved over the tracker board.

On the usual player piano the tracker board has 88 such openings, one for each of 30 the 88 keys of the piano key board and it is difficult to locate the note being sounded from an inspection of the paper sheet as it passes over the tracker board. By means of my invention I am not only enabled to locate 35 quickly and at once the exact note being sounded, but by means of my improvement a learner on the piano is greatly helped in studying a certain piece of music by listening to the music made by the player piano 40 and at the same time striking the several keys of the manual keyboard with the fingers in accordance with the designations indicating the notes being sounded by the player piano.

45 My invention consists of a designation member in the form of a bar adapted to be placed in front of the tracker board and in front of the perforated music sheet passing over same and provided with a miniature 50 reproduction or picture of the piano key-board, the representation of the several keys being adapted to accurately register with and be positioned in front of the tracker board openings adapted to effect the sounding 55 of the respective notes.

While the designation bar may be ar-

ranged in many ways for placing it in accurate registry with the tracker board and moving it out of the way so that the paper music roll can be readily placed in and removed from operating position, I preferably 60 pivotally mount the bar within the usual box or housing inclosing the tracker board, and adapted to readily swing into and out of operating position.

65 My invention also contemplates the provision of a light and reflector carried by the bar and adapted to illuminate the designations so that they can be readily seen. Another feature of my invention is to provide 70 means so that an operator can readily learn the positions of the various notes on the ordinary music staff by providing a representation of the ordinary music staff on the bar with note designations in their proper positions on the shaft and properly registered 75 with the key designations, and similarly registering with the respective perforations in the music strip.

80 My invention will be more readily understood by reference to said drawings, in which—

85 Figure 1 is a fragmentary front elevation of the tracker box of a player piano and embodying my invention in one form;

85 Fig. 2 is a vertical sectional view on the line 2—2 of Fig. 1;

90 Fig. 3 is a fragmentary view similar to Fig. 1 and illustrating another form of my invention;

90 Fig. 4 is a vertical section similar to Fig. 2 and taken on the line 4—4 of Fig. 3;

95 Fig. 5 is a fragmentary front elevation of an indicating bar equipped with a reflector;

95 Fig. 6 is a detail vertical section on the line 6—6 of Fig. 5;

100 Fig. 7 is a fragmentary elevation of an indicating bar equipped with a music staff and note designations;

100 Fig. 8 is an enlarged detail sectional view taken on the plane of the line 8—8 of Fig. 3.

105 In said drawings 1 presents the usual tracker board of a player piano or such like musical instrument, and provided with openings 2 in its front edge, which are connected in the usual manner to pneumatic player apparatus. There is one opening 2 for each key to be struck and it is common practice to provide one opening 2 for each 110 key of the piano, or commonly 88 of these openings.

The perforated music sheet 3 is mounted upon rollers 4 and 5 and is adapted to be unrolled from the upper roller in the operation of the player piano. This perforated sheet is provided with perforations or openings 6 which are adapted to register with the proper openings 2 in the tracker board to cause the proper notes to be sounded.

10 The rollers 4 and 5 and the tracker board are all mounted within a box or housing 7 commonly arranged within the casing of the piano and usually arranged above the manual keyboard of the piano. The box is 15 closed at its top, bottom and back and is provided with ends 8 upon which the rollers and the tracker board are mounted. The box is open at its front so that the paper sheets can be seen by the one operating the 20 player.

In operating the usual player piano the tracker board is covered or hidden by the moving perforated music sheet and it is 25 practically impossible for the operator to quickly and accurately locate, upon the key board of the piano, the note being sounded by any particular perforation in the music sheet. It is especially difficult in such constructions in which the keys of the 30 keyboard do not move upon the pneumatic operation of the piano.

I provide what I term a key designation bar 10 provided with a miniature representation 11 of the keyboard of the piano. This 35 representation of the keyboard extends longitudinally of the bar and the bar is adapted to be placed in horizontally extending position in front of the paper strip 3 and at such a height, relatively to the tracker 40 board that its upper edge is positioned substantially even with the row of holes 2 in the tracker board.

The several key designations 12 on the 45 bar 10 are arranged to accurately register with the respective openings 2 which operate to sound respective notes. For instance, a note which is sounded by any particular perforation in the paper music sheet, will 50 also be sounded by striking the piano key indicated by the key designation which registers with that particular perforation.

In the form of my invention illustrated 55 in Figs. 1 and 2 I pivotally mount the bar 10 within the housing 7. I provide the bar 10 with upward extending parallel rigid arms 13 at its ends and I pivotally mount the upper ends of said arm or cylindrical projections 14 which I secure upon the end walls 8 of the housing 7. For mounting 60 the arms on the pins I provide the arms with perforated bearing bosses 15 fitting upon the projections 14 and provided with flat outer faces 16, adapted to be engaged by flat holding springs 17 also mounted 65 upon the end walls of the box. I arrange

the flat faces 16 so that in one position the springs hold the bar in raised position as shown in dotted lines Fig. 2, and in another position the springs hold the bar in indicating position relatively to the tracker bar as 70 shown in full lines, Fig. 2. Thus the bar 10 can be readily moved out of the way to facilitate the changing of paper strips 3 and can as easily be returned to indicating position.

75

In Figs. 3 and 4 I have shown a form of my invention in which the bar 10 is hingedly mounted at one end to one end wall of the housing 7 and is thus arranged to swing around horizontally into and out of position instead of to be lifted up and down as in the other form. In this second form I provide one end of the bar 10 with a vertically extending rigid hinge member 18 and I provide upper and lower pivot lugs 19 secured to the end wall 8 of the housing and in which the end bar 18 is pivotally mounted. As in the former instance I provide a holding spring 20 secured to the end wall 8 and adapted to press against flattened surfaces 20' provided on the end bar to hold the designation bar 10 either swung into indicating position or to hold it swung out of the way to the left to permit the placement and removal of the perforated 95 music sheet.

80

90

95

As illumination is usually arranged, the shadow of the operator frequently falls upon the perforated music sheet and would render difficult the close observance of the 100 music perforations and the key designations 12 on the bar 10 and I therefore provide means for illuminating the bar 10. This means consists of an elongated reflector 21 which I secure to the under part of the bar 105 10 projecting in front of its middle portion and I arrange a small electric lamp 22 carried by the bar 10 and adapted by the aid of the reflector to illuminate the face of the bar 10. In this form I preferably slightly 110 concave the face of the bar 10 as shown at 23 so as to aid in the illumination thereof by the lamp 22.

105

110

To aid in determining the note on a music staff which corresponds with any particular perforation in the music sheet 3, I provide a staff 24 on the bar 10 below the key designations. This staff consists of the usual horizontal parallel lines 25, and I place on the shaft, note designations 26 corresponding with the key designations immediately above. By this means an operator can readily determine not only the key on the keyboard of the piano corresponding with any particular perforation but is also 120 aided in reading music or in translating the perforated music into note music.

120

As many modifications of my invention will readily suggest themselves to one skilled in the art I do not limit or confine 130

my invention to the particular structures herein shown and described.

I claim:

1. In a player piano, the combination of 5 a roller box having side walls, a tracker board in said roller box for coöperation with a perforated sheet of music, a key designation bar adapted to be swung into position adjacent said tracker board, a pivot support on the end wall of said roller box, a pivotal extension on said key designation bar having pivotal mounting on said pivot support, a plurality of flat detent surfaces on said pivotal extension and a leaf 15 spring fixedly mounted and adapted to bear on said flat surfaces for retaining said key designation bar in its operative and inoperative positions.

2. In a player piano, the combination of 20 a roller box having end walls, a tracker bar in said roller box adapted for coöperation with a perforated sheet of music, a key designation bar adapted to be swung into and out of operative association with said sheet 25 of music at a point adjacent said tracker bar, a pivot bracket on the end wall of said roller box, a pivotal hub on said key designation bar, said pivotal hub being mounted on a vertical axis on said pivot bracket for

horizontal swinging motion of said key designation bar, a plurality of flat surfaces formed on said pivotal hub, a detent leaf spring fixedly mounted in said roller box, and engaging with said flat surfaces for retaining said key designation bar in its operative or inoperative positions. 30

3. In a player piano, the combination of a roller box having end walls, a tracker bar in said roller box adapted for coöperation with a perforated sheet of music, a key designation bar adapted to be swung horizontally 40 into and out of operative association with said sheet of music at a point adjacent said tracker bar, a pivot bracket on the end wall of said roller box comprising a pair of 45 spaced pivot hubs in vertical alinement, a pivot extension of T formation on the end of said key designation bar, said T extension comprising a pair of pivotal hubs mounted on a vertical axis between said 50 first pivot hubs, a plurality of flat detent surfaces on said T extension, and a leaf spring bearing on said flat surfaces for retaining said key designation bar in its various horizontal positions. 55

In witness whereof I hereunto subscribe my name this 15th day of February, 1919.

CARL H. MAYER.
